(57) **CLAIM**

The ornamental design for a case for portable display device, as shown and described.

DESCRIPTION

1. Case for portable display device

1.1 : Front Perspective, showing the support feature in a folded configuration

1.2 : Front, thereof

1.3 : Back, thereof

1.4 : Left, thereof

1.5 : Right, thereof

1.6 : Top, thereof

1.7 : Bottom, thereof

1.8 : Front Perspective, showing the support feature in an unfolded configuration

1.9 : Front, thereof

1.10 : Back, thereof

1.11 : Left, thereof

1.12 : Right, thereof

1.13 : Top, thereof

1.14 : Bottom, thereof

1.15 : Back Perspective, showing the handle feature in an example configuration of use

Reproductions 1.1 to 1.7 are views showing that a supporting part on the rear surface of the case for portable display device is folded, Reproductions 1.8 to 1.14 are views showing that the supporting part on the rear surface of the case for portable display device is unfolded, and Reproduction 1.15 is a view showing that a handle on the rear surface of the case for portable display device stands, for use.

1 Claim, 15 Drawing Sheets
